UNITED STATES PATENT OFFICE.

HENRY H. LOCKE, OF PLEASANTVILLE, PENNSYLVANIA, ASSIGNOR TO
DOUGLAS BLY, OF ROCHESTER, NEW YORK.

IMPROVEMENT IN PUMP-ROD ATTACHMENTS.

Specification forming part of Letters Patent No. 103,632, dated May 31, 1870; reissue No. 4,632, dated December 26, 1871; reissue No. 5,543, dated August 19, 1873; application filed August 9, 1873.

To all whom it may concern:

Be it known that I, HENRY H. LOCKE, of Pleasantville, in the county of Venango and State of Pennsylvania, have invented a certain Improvement in Pump-Rod Attachments, of which the following is a specification:

This invention consists of an attachment for a pump-rod, whereby the same may be adjusted in place and readily clamped in position, as hereinafter described.

In the drawings, Figure 1 is an elevation of my improved attachment with a pump-rod connected therewith; Fig. 2, a horizontal section in line *x x*; Fig. 3, a plan of the clamping-bolt detached.

A represents the cross-head or bearing-block, which has an axis, *a*, that rests in the end of the working-beam and forms the joint to allow the necessary oscillation at different points of the stroke. *D* is the clamping-head, and *E* is the connecting portion between the cross-head and the clamping-head. A longitudinal aperture is formed through the cross-head *A*, connecting portion *E*, and clamping-head *D*, to receive the pump-rod *B*, which may be adjusted up and down therein, being held at different positions by the clamping-bolt hereinafter described. The clamping-head is also formed with a socket at right angles to the rod, having a shoulder or stop, and in this socket fits the clamping-bolt *C*. This bolt is formed with an opening or passage, *e*, of sufficient size to receive the rod *B*, and allow its ready adjustment up or down. The bolt is provided with a screw-shank, *f*, which extends

through the clamping-head, and has a nut, *g*, screwed upon its end, by which it is tightened in place.

The bolt *C* being inserted in its place, as shown in Fig. 2, the pump-rod *B* is passed through its opening, when, by tightening up the clamping-bolt, the rod is clamped or gripped and held firmly in place between the bolt and the clamping-head. This action is produced by the wedge action of the opening in the clamping-bolt and the contact against the clamping-head.

This arrangement is particularly adapted to deep-well pumps, which require a nice adjustment of the rod to adapt the piston to proper action with the valve.

What I claim, and desire to secure by Letters Patent, is—

1. A pump-rod attachment consisting of a cross-head, *A*, which forms the pivotal bearing, and a clamping-head, *D*, which forms the point of attachment for the pump-rod, when said parts are distinct from each other, and are connected by an intermediate part, *E*.
2. The clamping-bolt *C*, having a transverse opening or passage, *e*, in combination with a clamping-head, *D*, for the purpose of allowing the adjustment and producing the clamping of a pump-rod.

In witness whereof I have hereunto set my hand this 7th day of August, 1873.

H. H. LOCKE.
